UNITED STATES PATENT OFFICE.

FOSTER J. BORDEAUX, OF BOSTON, MASSACHUSETTS, ASSIGNOR TO AUTOMATIC APPLIANCE COMPANY, OF BOSTON, MASSACHUSETTS, A CORPORATION OF MASSACHUSETTS.

STARTER FOR INTERNAL-COMBUSTION ENGINES.

1,128,219.

Specification of Letters Patent. Patented Feb. 9, 1915.

Application filed April 24, 1913. Serial No. 763,197.

To all whom it may concern:

Be it known that I, FOSTER J. BORDEAUX, a citizen of the United States, and resident of Boston, in the county of Suffolk and State of Massachusetts, have invented new and useful Improvements in Starters for Internal-Combustion Engines, of which the following is a specification.

My invention consists in improvements in starting devices for internal combustion engines, and comprises devices which automatically disengage the starter from the engine shaft in case of premature firing, and also automatic devices to reduce the liability of premature firing taking place.

Other details of my improvements will appear from the specification which follows.

In the drawings hereto annexed which illustrate my improved engine starter, Figure 1 is a front elevation of a portion of an engine casing with the starter devices applied thereto; Fig. 2 is a plan view of the same; Fig. 3 is a vertical longitudinal section on a larger scale showing the end of the engine shaft with portions of the starting mechanism attached thereto; Fig. 4 is a vertical cross section of the same; and Fig. 5 is a detail view on an enlarged scale showing a portion of the starting mechanism.

Referring first to Figs. 1 and 2, C represents the front plate of the crank case casting of an automobile engine. To this front plate upon a suitable bracket A there is journaled the wheel W which is grooved to carry the cord or belt B, the latter being secured to the wheel W at B'. Secured to and preferably integral with the wheel W there is provided the chain pinion A' and the spark retarding cam A'', the chain D being secured to the chain pulley A' at A''.

To attach the starting device, the crank shaft S is cut off at a point closer to the engine casing C than is usual, to provide space between the shaft S and the usual cranking shaft C' for the starting mechanism. The shaft S receives the member E which is secured to the shaft, as by a pin E', this member having a stud portion E'', which is, in effect, a prolongation of the shaft S. On the outer end of the stud E'' there is secured the ring ratchet C' with its teeth C'' by means of the pin E'', this ring

ratchet being adapted to receive the teeth or pins on the cranking shaft C' in the usual manner. A pulley F is journaled to turn freely on the shaft extension E', and is preferably mounted thereon by means of ball bearings. The shaft extension E' has formed upon it ratchet teeth E'', which are adapted to coact with the pawl F' which is pivoted at F' on the pulley F, which is chambered at F'' to provide a housing for the pawl F'. This pawl has a single tooth F'' to engage with the teeth E'' of the ratchet on the shaft extension E'. Moreover, the pawl F' is a pulling pawl, as distinguished from a pushing pawl; the pivot F'' being in advance of the tooth F'' in the direction of rotation when the shaft S is being rotated by means of the pawl F'. The employment of a pulling pawl facilitates disengagement of the engaged teeth, F'' and E'' if by chance the engine should reverse fire. As the pivot F'' lies outside the periphery of the ratchet extension E', the relative movement of the faces of the teeth F'' and E'', during disengagement, is not a rubbing movement, but one of clearance.

The means to rotate the pulley are represented by the chain D secured to the chain pinion A' at A'' and to the pulley F at D'. When the cord B (which may extend back through the dash of an automobile) is pulled, the chain D rotates the pulley F in a right-handed or clockwise direction, as viewed in Figs. 1 and 4. A retaining finger L is secured to the pulley F and is provided with a projection L' which overlies the extension F'' on the pawl F', and a spring K attached to the retaining finger L' stresses the pulley F in a left-handed direction or anti-clockwise, as viewed in Figs. 1 and 4. The normal direction of rotation of the shaft S in the instance illustrated is right-handed or clockwise as viewed in Figs. 1 and 4.

When by means of the chain D the pulley F is rotated, the pawl F' both by its own weight and also by the action of the projection L' on the retaining finger L, moves its tooth F'' into engagement with one of the ratchet teeth E'' of the shaft extension E' and thus the engine shaft S is rotated. When the pull on the cord or belt B is released, the spring K draws the retaining

finger L downward and carries with it the pawl F' by means of the overlying projection L', until the extension F² of the pawl F' strikes the edge G' of the releasing stop G, this latter being so formed as to constitute a housing and protection below the pulley F. The shape of the ratchet teeth E⁴ and the location of the pivot F³ outside of the shaft extension E², causes the tooth F⁴ to move outward in a circular path, so that the movement of the tooth F⁴ is one of retraction from a ratchet tooth E⁴. This movement of retraction is made possible by using a pulling pawl as distinguished from a pushing pawl, and locating the pawl pivot outside the ratchet periphery.

If, by chance, the engine should back-fire so as to give the shaft S a reverse movement, the pulley F will be turned sharply in the reverse direction and will instantly cause the extension F² to collide with the releasing stop G' and thus disengage the pawl F' from the ratchet tooth E⁴ with which it was engaged when the chain D was operated. In order to guard against accidents of this sort, the spark timer I is provided with a retarding bar H which, when the cord or belt B is drawn, is pushed by the spark retarding cam A² to such a position that the timer I retards the spark.

The extension E, as shown in the drawings, may with convenience be made to supply the place of a fan-belt pulley which may be slipped on the larger portion of the extension E wherethrough the pin E' passes.

All the working parts of the starter above described are so attached as to partake of any movement of the engine base relatively to the framework on which it is suspended, so that no oscillations or movements of the engine as a whole can affect the starter, or disarrange the relationship of its parts. An exception to this may be furnished by the member G, which may be attached to the automobile frame, and not to the engine,

without materially affecting the operation of the starter.

I claim:

1. In a starter for internal combustion engines, the combination of the engine shaft, a pulley mounted to turn on said shaft, a ratchet on the shaft inclosed by the pulley, said pulley being chambered through part of its circumference to form a housing for a pawl, the pawl, housed in the pulley chamber and pivoted near the periphery of the pulley and having a projection extending beyond the periphery of the pulley, a stop external to the pulley, to coact with the pawl projection and disengage the pawl from the shaft ratchet, means to turn the pulley, and means to engage the pawl and ratchet when the pulley is turned in engine-starting direction.

2. In a starter for internal combustion engines, the combination of the engine shaft, a pulley mounted to turn on said shaft, a ratchet on the shaft inclosed by the pulley, said pulley being chambered through part of its circumference to form a housing for a pawl, the pawl, housed in the pulley chamber and pivoted near the periphery of the pulley and having a projection extending beyond the periphery of the pulley, a stop external to the pulley, to coact with the pawl projection and disengage the pawl from the shaft ratchet, means to turn the pulley, and means to engage the pawl and ratchet when the pulley is turned in engine-starting direction, said pulley turning means comprising devices to retard the spark timer when the said pulley is turned in engine starting direction.

Signed by me at Boston, Massachusetts, this 17th day of April 1913.

FOSTER J. BORDEAUX.
